UNITED STATES PATENT OFFICE

ALVAH H. LAWRENCE, OF HAMLET, INDIANA

DIRIGIBLE AIR SAILING CRAFT

Application filed April 15, 1929. Serial No. 355,110.

My invention relates to improvements in dirigible air sailing craft and it more especially consists of the features pointed out in the annexed claims.

The purpose of my invention is to provide a lighter than air craft which will afford a high degree of efficiency in creating a vacuum in front of the air ship to reduce resistance to its forward movement and at the same time utilize the density of the air at the rear or sides of the ship to propel it; that combines with a ship water floatable cabins and water sailing propellers and rudder; that may arrange air propellers alongside of the ship adjustable in a horizontal and vertical direction; that provides a central power station to generate electricity for the different motors used to operate the ship; that centralizes the control in a pilot's cabin; and that uses the adjustable propellers as accessory steering ascending and descending means.

A further object is to provide an airship that may be held motionless in the air; that may be directly raised or lowered; that may be bodily moved sideways; that may be steered by the cooperation of the different motors; that uses the motors positioned at the extreme outer angles of transverse quadrilateral or other angularity frames so as to be in free air without having their efficient operation reduced by the near proximity of the ship's body; that may if desired have the cabin within the body; and that through the use of my propelling system the ship can be raised vertically without loosing ballast and lowered vertically without the loss of gas from the buoyancy cells.

With these and other ends in view, I illustrate on the accompanying drawing such instances of adaptation as will disclose the broad underlying features of my invention without limiting myself to the specific details shown thereon and described herein.

Figure 1 is a diagrammatic side elevation. Fig. 2 is a diagrammatic front elevation showing the main frames in dotted lines.

Fig. 3 is a front elevation of an adjustable propeller drive.

Fig. 4 is a diagrammatic representation of

a simple form of motor controls located in the pilot's cabin.

Fig. 5 is a diagrammatic plan view of Fig. 1.

In carrying my invention into commercial use I may employ whatever equivalents or alternatives of construction that the varying exigencies of different conditions may demand without departing from the broad spirit of the invention.

The air ship comprises an air floatable body 1 to which is suspended a water floatable cabin 2. Near the bow at the top of the body a pilot's cabin 3 is placed. A power plant 4 may be located at the rear end of the cabin 2. This power plant furnishes light for the ship and power for the air propellers. It also has connected therewith a water propeller 5 placed in advance of a water steering rudder 6. This arrangement serves as an emergency equipment, in case the air ship for any reason is obliged to descend onto a body of water. It may be controlled in the air by a steering rudder 7 and altitude wings 8. These conventional means are accessory to universally mounted, individually driven air propellers 14 which by reason of their being adjustable both in a horizontal and vertical direction simultaneously throughout 360 degrees on two planes at right angles to each other assist in driving the ship straight ahead, right or left, and up or down, as desired. In the use of the words, through 360 degrees, or throughout 360 degrees, or throughout more than 360 degrees, in the claims or in the specification, I do not limit myself to these exact degrees as an approximation of them falls within the scope of my invention.

An important feature of my invention is the use of a puller air propeller 10 placed at the bow of the ship, in order to create a vacuum by the rapid removal of the air from in front of the bow through the longitudinal tube 9. On each side of the ship at its stern is placed a pushing air propeller 11 which cooperates with the propeller 10 at the bow, the latter reducing the air

resistance and the former acting against the dense air at the rear.

The body 1 may be formed of any desired number of tetrahedral frames 12, of which only four are shown in Fig. 1. The center square of each frame forms an opening through which the lengthwise air shaft 9 passes. The interior of the body may be arranged as desired for the reception of the 10 gas containers. Stairways, passageways, etc., from one part of the ship to another may be placed where most needed to afford communication between the pilot's cabin, the adjustable propellers, the main cabin, the 15 power plant, the pulling and pushing propellers, etc., etc., (not shown).

A main supply line 13 extends from the power plant 4 to the pilot's cabin, and distributing lines 21 lead from there to the different motor drives. Any desired type of 20 switching system, exemplified only diagrammatically in Fig. 4, may be used. This feed line 22 serves the horizontally adjusting motor 17, feed line 23 serves the vertically 25 adjusting motor 18, and feed line 24 serves the motor which drives the propeller 14. The propellers 14 may be directed up or down by motors 18, and to the right or left by motors 17, from the pilot's cabin, as needed. The connections may comprise any form 30 of remote controls that are well known so as to start, stop, and reverse the motors 17 and 18, and the driving motors for the sailing propellers 14, and the driving propellers 35 10 and 11. This type of connections with the cooperative motor windings is so well known that they are not shown.

The motors 17 and 18 are suitably supported in frames 15. Motor 17 is supported 40 by the frame 15 which turns on vertical pivots 20. In the frame 16 the motor for the propeller 14 is positioned. It has movement on the horizontal pivots 19. Each of the motors 17 and 18 may be connected to the 45 respective pivots 20 and 19 by any form of well known worm drive.

If desired, any form of control 50 may be placed in the air shaft 9, as a door or otherwise, to retard the passage of air through the shaft or tunnel, close it entirely or leave it wide open. A separate motor 26 is indicated diagrammatically in Fig. 1 for operating the door in either direction, the motor being under remote control from the pilot's cabin, 55 in a well known manner, similar to the controls for motors 17 and 18. The motors for the propellers 10 and 11 may also be controlled for stopping, starting, and reversing, by any well known type of remote control.

60 The ship is controlled in the main from the pilot's cabin by means of the motors 17, 18, 10, 11 and 26, and accessory rudders 7 and 8. In case of forced landings on water, the rudder 6 and propeller 5 will be brought 65 into service. The frames 16 may be made

large enough so that the propellers 14 can be set to rotate in a horizontal plane to assist in raising or lowering the ship. By reason of this expedient the ship can be maneuvered with great certainty and safety. Motors 17 and 18 may be positioned wherever desired 70 on the body 1, as shown in Figs. 1 and 2 they are supplemented by vertical and horizontal air rudders.

The motors 17 and 18 have been referred to 75 as capable of being stopped, started and reversed. The motors need not however be reversed as the frame 16 can be rotated 360 degrees, and the motor 28 can also be swung on the pivots 19 throughout 360 degrees, 80 which facility may be taken advantage of instead of reversing the motors, it being only necessary to stop them at selected positions in any well known manner. The motors 28 for the propellers 14, motors 29 for the propellers 11, and motors 30 for the propeller 10, as well as the motor 31 for the turbine 85 or propeller 27, may all be reversible as desired.

It is understood that though I have shown 90 propellers driven by electric motors I do not limit myself to the exclusive use of electricity as any other source of power may be used.

What I claim is:

1. In lighter than air ships, an air floatable 95 body, a longitudinal air passage extending throughout the length of the ship, a propeller at the bow of the ship positioned in front of the air passage for pulling purposes, and a pair of propellers at the stern of the 100 ship positioned one on each side of the air passage and at the rear of the horizontal rudders.

2. In air traversing ships, an air floatable 105 body, a cabin and a power plant suspended therefrom, a plurality of electric motors and propellers attached to the ship, and means for swinging the motors vertically through 360 degrees and horizontally through 360 degrees, independently of each other, or simultaneously, to move the ship bodily forward or backward, or upward or downward and to the right or left independently of steering directions.

3. In lighter than air ships, an air floatable 115 body, a plurality of motor driven propellers attached to the body the motors being adapted to operate the propellers in different planes throughout 360 degrees independently of each other at right angles to each other, and a power plant in common for the motors.

4. In floatable air ships, an air floatable 120 body, propellers for driving the ship, separate propellers operable independently on separate planes throughout 360 degrees at right angles to each other adapted to accelerate, retard, directly raise and lower the ship, and accessory air rudders attached to the ship whereby during cruising the main propellers will move the ship forward and the 125 130

separate propellers will directly raise or lower it or bodily move it sideways or hold it at rest or in movement at a given elevation, or counteract the main propellers in stopping.

5 5. In combination, an air floatable body, a supporting water floatable cabin, a plurality of quadrilateral frames to which the body and cabin are attached, and a plurality of motors positioned at the extreme outer
10 angles of the frames.

6. In air ships, an air floatable body having an air shaft extending throughout the length thereof such shaft being enlarged conically at the bow of the ship, two separate
15 systems for moving the ship, one comprising a propeller positioned in advance of the air shaft and on each side horizontally of the shaft at the stern of the ship, and independent propellers positioned adjacent the sides
20 of the ship adapted to operate throughout 360 degrees in more than one plane and adapted to move the ship up or down, sideways and forward or backward independently of the cruising propellers.

25 7. In air ships, an air floatable body, a supporting water floatable cabin, two separate systems for moving the ship, one comprising a propeller positioned at the bow of the ship and on each side horizontally at
30 the stern of the ship for cruising purposes, and another comprising independent propellers positioned adjacent the sides of the ship on the plane of the bottom and the top
35 adapted to operate throughout more than 360 degrees in more than one plane independently of each other for moving the ship up or down, sideways or forward or backward independently of the cruising propellers or holding the ship motionless in the
40 air.

In testimony whereof I affix my signature.
ALVAH H. LAWRENCE.
